INVENTOR.
Peter Becsi

UNITED STATES PATENT OFFICE.

PETER BECSI, OF DURAND, MICHIGAN.

BLOTTER DEVICE FOR PENS.

Application filed February 8, 1926. Serial No. 86,947.

This invention relates to improvements in blotters and has for its object to provide a blotter device to be carried on a pen.

Another object of the invention is to provide a carrier on which a clip is pivotally supported, said clip adapted to engage a fountain or other pen, and a roller on said carrier upon which a blotter is removably mounted.

10 Another object of the invention is to provide a tubular blotter and a roller upon which said blotter is adapted to be removably mounted.

A still further object of the invention is 15 to provide a device of this character which will be practical and efficient in use, cheap to manufacture, strong and durable.

Still another object of the invention is 20 to provide a blotter carrier of resilient material having a roller pivoted thereto and means for fixing the same to a fountain pen, said roller being removable whereby a blotter may be changed when necessary.

With the above and such other objects in 25 view, as may hereinafter more fully appear, I have invented the device shown in the accompanying drawings, in which:

Figure 1 is a side elevational view of a pen, embracing my invention;

30 Figure 2 is a similar view, showing a changed position of a blotter;

Figure 3 is an end, elevational view thereof, showing the blotter in the act of being removed from its carrier;

35 Figure 4 is a section on line 4—4 of Figure 5;

Figure 5 is a plan view of my device, partly broken away;

40 Figure 6 is a section on line 6—6 of Figure 5; and

Figure 7 is a perspective view of the blotter tube.

Like reference characters indicate like parts throughout the following specification 45 and in the several views in the drawings, in which 1 indicates a pen, having mounted thereon a carrier 1' having a clip 2, pivotally supported thereon, and held in fixed position by means of a leaf spring 3, to 50 which the clip pivot 4 is riveted. The clip 2, is provided with indentations or struck out portions 5, which engage in similarly formed indentations 6, in the base 7 of the clip member. The carrier member 1' tapers 55 from the center, toward each end 8 and 9,

having right angular terminals with apertures 10 and 11 therein, forming bearings for the pins 12 and 13 of the roller 14, upon which a blotter tube 15, is removably mounted. The carrier member 1' may be 60 made of resilient material whereby either end 8 and 9 may be sprung out of engagement with the pins 12 and 13, as illustrated in Figure 3, in order to remove the roller 14, and take off used or worn out blotters 65 and replace the same with new ones.

The roller 14, may be made of wood, fiber, rubber or any other suitable material and of any desired size. The blotter tubes may be cut the exact length of the roller 14, or 70 they may be made in longer lengths and cut as required for use.

From the above description it will be obvious that I have provided a simple, inexpensive blotter attachment for fountain or other 75 pens which may be quickly and readily attached to pens, and just as quickly removed, and on which the blotter tubes may be readily attached and detached. Thus, with the use of my blotter carrier, the operator will 80 always have a blotter convenient and ready for use.

The device may be used either longitudinally of the pen, as indicated in Figure 1, or transversely of the pen as shown in 85 Figure 3, locking means being provided to hold the carrier in either position.

Having described my invention that which I claim to be new and desire to procure by Letters Patent is:

1. In a blotting device, a roller, a blotter tube removably mounted thereon, a carrier for the roller and a clip rotatably mounted on the carrier centrally thereof, and means for locking this clip and carrier. 90

2. In a blotting device, a roller, a blotter tube removably mounted thereon, a carrier for the roller and a clip rotatably mounted on the carrier centrally thereof, and means for locking this clip and carrier in parallel 100 relation.

3. A carrier, a roller, a blotter tube slidably mounted on the roller, a clip pivotally connected to said carrier, a rivet member and a leaf spring carried by the rivet to 105 normally hold the carrier and clip in relatively locked position to which said pivot is riveted.

4. In a blotting device, a roller, a blotter tube removably mounted thereon, a carrier 110

- for the roller and a clip rotatably mounted on the carrier centrally thereof, and means for locking this clip and carrier in parallel relation and in transverse relation.
5. In a blotting device, a roller, a blotter tube removably mounted thereon, a carrier for the roller and a clip rotatably mounted on the carrier centrally thereof, and means for locking this clip and carrier in parallel relation and in transverse relation, said means including a leaf spring.
6. In a blotting device, a roller, a blotter tube removably mounted thereon, a carrier for the roller and a clip having a depression 10 rotatably mounted on the carrier centrally thereof, and means for locking this clip and carrier in parallel relation and in transverse relation, said means including a leaf spring
- 15

and projection on the carrier adapted to seat in said depression in the clip.

7. In a blotting device, a roller, a tube formed of a single layer of blotting material, said tube being removable from the roller, said tube and roller being of substantially even lengths, and a spring clip carrier for 25 the roller, and a spring controlled spring clip upon which the carrier is mounted.

8. A device of the character described embracing a carrier, a blotter roller rotatably mounted thereon, and a clip rotatably 30 mounted thereon, and means for holding said carrier and clip locked in a plurality of positions.

In testimony whereof I affix my signature.

PETER BECSI.
